UNITED STATES PATENT OFFICE.

PERLEY L. KIMBALL, OF BELLows FALLS, VERMONT, ASSIGNOR TO THE VERMONT FARM MACHINE COMPANY, OF BELLows FALLS, VERMONT, A CORPORATION OF VERMONT.

CENTRIFUGAL SEPARATOR.

SPECIFICATION forming part of Letters Patent No. 751,178, dated February 2, 1904.

Application filed April 22, 1901. Serial No. 56,853. (No model.)

To all whom it may concern:

Be it known that I, PERLEY L. KIMBALL, a citizen of the United States of America, residing at Bellows Falls, in the county of Windham and State of Vermont, have invented a certain new and useful Improvement in Centrifugal Separators, of which the following is a description, reference being had to the accompanying drawings, wherein—

10 Figure 1 is a view in central vertical section of an apparatus embodying said improvement. Fig. 2 is a side elevation of the partition, approximately cylindrical in form, which is carried within the separator-drum. Fig. 3 is a view of an apparatus embodying said improvement in horizontal cross-section on the plane denoted by *x* *x* looking downward. Fig. 4 is a perspective view of a liner made according to my invention. Fig. 5 is a plan view of the 20 top of the device, showing the outlets.

The object of the improvement is the production of an apparatus for separating mixed liquids of different densities, notably for separating cream from new milk.

25 The apparatus will herein be described as applied to the separation of cream from new milk.

In the accompanying drawings, the letter *a* denotes a separator-drum which in use and 30 practice rotates very swiftly, some six or seven thousand turns a minute.

The letter *b* denotes the cover of the separator-drum. Its lower part is conical and its upper part cylindrical. When the apparatus 35 is in use, the drum is secured to the cover by the ring-nut *c*.

The letter *d* denotes packing, of rubber or the like, which may be cemented to the drum-cover for making the joint tight between the 40 drum and the cover. In order to hold the drum and the cover stationary each with the other while the ring-nut is being screwed into place or removed therefrom, the cover is provided with a tenon *b'*, which fits into a corresponding mortise in the interior wall of the separator-drum.

The letter *e* denotes a thimble which is fastened into the upper end or neck of the cream-

disk. It is pierced centrally by an inlet for full milk and non-centrally for the adjustable 5° cream-outlet *f*.

The letter *g* denotes what may be termed the "cream-disk." It, like the cover, is conical in its lower part and cylindrical in its upper part. It fits within the cover. It is supported 55 at the top of the cover and maintained in a central position by the spacing-blocks *g'* *g''*. The wings *g* are for the purpose of causing the milk to rotate with the bowl. The cream-disk *g* may rest upon the upper end of the 60 separator-drum, or it may be separated therefrom a short distance, as shown in Fig. 1 of the drawings. This disk *g* catches the cream as it rises and practically conducts it to the adjustable cream-outlet. The skim-milk rising 65 on the interior wall of the drum passes over the top of the cream-disk and out through the adjustable skim-milk outlets *h*.

The letter *i* denotes a milk-tube, which at the upper end communicates with the full-milk inlet in the thimble *e*. This milk-tube extends to near the bottom of the separator-drum and there delivers the full milk below the plate *k*. This plate *k* has perforations *k'*, through which the milk rises to begin the 75 process of separating the cream from the milk. This plate *k* extends to practical contact with the interior of the separator-drum, not, however, making an absolutely tight joint therewith. On its under side the plate *k* carries 80 supports *k''*, which rest on the floor of the separator-drum and raise the plate *k* a little above the same.

The letter *l* denotes radial wings carried by the milk-tube, it being their function to aid in 85 making the milk take the rotation of the whole apparatus.

The letter *m* denotes as a whole and in a general sense a partition which is as a whole approximately cylindrical in form. It rests on 90 the plate *k'*. It is provided with passages *n* to permit the outward movement of the milk and the inward movement of the cream. These passages are arranged spirally from top to bottom of the partition and are bounded by plates 95 which are integrally united one with the other,

there being a suitable stiffening-ring at each end of the liner. The plates are so positioned that the milk is caused to travel laterally in order to pass through the passages. These 5 plates are grooved, as at m^2 , to facilitate the inward movement of the cream. The outer edges of the plates are turned outwardly to form lips n , which extend to practical contact with the interior wall of the separator-drum, 10 and thus keep the partition in place.

The tenon o , extending upward from the floor of the separator-drum, passes into a corresponding mortise in the plate k and so aids in making that plate rotate in unison with the 15 separator-drum. The contact of the lips m' with the interior wall of the separator-drum helps the cylinder m to rotate in unison with the separator-drum.

In the practical use of this device the full 20 milk enters the full-milk inlet, passes down the milk-tube and out at the lower end thereof, and rises through the perforations in the plate k , thus reaching the interior of the partition m . The swift rotation of the whole apparatus tends to make the cream seek the center, and the more watery portions, known as 25 "blue milk," seek the walls of the separator-drum. The peculiar formation of the cylinder m , already described, facilitates the separation 30 of the cream from the blue milk. The cream, seeking the center, readily flows through the passages n , on the inner side thereof, at the same time that the blue milk flows outwardly through the same passages, at the 35 outer side thereof. The cream, which accumulates in the center, rises against the cream-disk and passes out of the apparatus through the adjustable cream-outlet. The blue milk, which has reached the wall of the separator- 40 drum, rises and passes over the outside of the cream-disk and through the adjustable skim-milk outlets.

It will be observed that the use of an adjustable cream-outlet and also an adjustable skim-milk outlet doubles or duplicates the possibilities of adjusting the device to its work. 45

I claim as my improvement—

1. In combination the separator-drum, the drum-cover having a conical lower part and 50 cylindrical upper part, the cream-disk held within the drum-cover and having conical lower part and cylindrical upper part, the thimble in the upper end of the cream-disk pierced by the central inlet for full milk, and 55 a vertically-arranged adjustable outlet for the cream, substantially as described and for the purposes set forth.

2. In a separator the drum, the drum-cover having a lower conical part and upper cylindrical part, the cream-disk held within the drum-cover and having a conical lower part and a cylindrical upper part, the thimble in the upper end of the cream-disk pierced by a central inlet for milk and a vertically-arranged adjustable outlet for cream, in combi- 65

nation with a laterally-arranged adjustable outlet for milk through the cylindrical part of the drum-cover, substantially as described, and for the purposes set forth.

3. In combination; the separator-drum, the drum-cover, the thimble in the upper end of the cream-disk pierced by central inlet for full milk and non-central outlet for cream, the milk-tube communicating with the central inlet for full milk and extending to near the bottom of the drum and adapted to deliver milk below the plate next mentioned, the plate duly supported near the bottom of the drum, extending to contact with the interior wall of the drum, and perforated by milk-orifices, 80 and a partition approximately cylindrical in form supported on said plate, all substantially as described and for the purposes set forth.

4. A liner having a multiplicity of slots therethrough, the walls of which are arranged 85 angularly with respect to the wall of the liner and thus give direction to the slots across the radial lines from the axis of the liner.

5. A liner substantially cylindrical in form having a multiplicity of slots therethrough, 90 the bounding-walls of said slots being bent at an angle to the liner-wall, thus directing the fluid moving in the passages formed by said slots across the radial lines of the liner.

6. A liner substantially cylindrical in form 95 having a multiplicity of slots therethrough, the bounding-walls of said slots being arranged angularly with respect to the liner-wall, the outer edges of said bounding-walls being bent outwardly to form lips.

7. A liner substantially cylindrical in form having a multiplicity of vertical slots therethrough, the bounding-walls of said slots being bent out of the tangential plane of the liner-wall, thus directing the fluid moving in the 105 passages formed by said slots across the radial lines of the liner.

8. A liner substantially cylindrical in form having a multiplicity of slots therethrough, the bounding-walls of said slots being arranged 110 angularly with respect to the liner-wall, thus directing the fluid moving in the passages formed by said slots across the radial lines of the liner, and grooves formed in the bounding-walls of the slots.

9. A liner substantially cylindrical in form having a multiplicity of slots therethrough, the bounding-walls of said slots being arranged angularly with respect to the liner-wall, thus 120 directing the fluid moving in the passages formed by said slots across the radial lines of the liner, and lengthwise grooves formed in the bounding-walls of the slots.

10. A liner substantially cylindrical in form having a series of circumferential rows of 125 slots therethrough, the bounding-walls of said slots being arranged angularly with respect to the liner-wall, the slots in one row being staggered with respect to those in the next adjacent row.

11. A liner substantially cylindrical in form having a series of circumferential rows of vertical slots therethrough, the bounding-walls of said slots being bent out of the tangential plane of the liner-wall, the slots in one row being staggered with respect to those in the next adjacent row.

12. A liner substantially cylindrical in form having a series of circumferential rows of ver-

tical slots therethrough, the bounding-walls of said slots being bent out of the tangential plane of the liner-wall, the slots in one row overlapping those in the adjacent rows, and being staggered with respect thereto.

PERLEY L. KIMBALL.
